RICHARD LABORDA, OF SAN FRANCISCO, CALIFORNIA.

FEED-GUIDE AND FOLDING ATTACHMENT FOR IRONING-MACHINES.

1,235,207.

Specification of Letters Patent. Patented July 31, 1917.

Application filed May 24, 1916. Serial No. 99,657.

To all whom it may concern:

Be it known that I, RICHARD LABORDA, a subject of the King of Spain, residing at the city and county of San Francisco and

5 State of California, have invented a new and useful Improvement in Feed-Guides and Folding Attachments for Ironing-Machines, of which the following is a specification.

10 This invention relates to a feed guide and folding attachment for ironing machines.

It is an object of the present invention to provide a simple, cheaply manufactured 15 folding attachment for flat-work ironing machines which will receive and fold flat articles, such as napkins, handkerchiefs, etc., when they are discharged from the machine and in conjunction with same a feed guide 20 attachment to permit alinement of the articles to be ironed with relation to the folding attachment when they are placed upon the feed belt. Further objects will herein-after appear.

25 The invention consists of the parts and the construction and combination of parts as hereinafter more fully described and claimed, having reference to the accompanying drawings, in which—

30 Figure 1 is a central, vertical section through a standard ironing machine known as a "six roll flat work ironer."

Fig. 2 is a plan view of the discharge end of the machine showing the position of the 35 folding attachment.

Fig. 3 is a plan view of the feed belt, showing the position of the feed guides.

Referring to the drawings in detail, and 40 particularly to Fig. 1 which is a central, vertical, longitudinal section through a six roll flat work ironer, A indicates the steam chest; 2 the upper ironing surface; 3 the padded rolls operable in conjunction with same; 4 the lower ironing surface; 5 the 45 upper apron; 6 the rolls by which said apron is supported and driven; 7 the lower apron; 8 the rollers upon which said apron is supported and driven; 9 the feed belt upon which the articles to be ironed are 50 placed; and 10 the rollers upon which the feed belt is supported and driven. All the 55 rollers, belts and aprons here shown are journaled in the frame, generally indicated at B, and form no part of the present invention.

The invention involved consists of an at-

achment which receives and folds the articles ironed as they are discharged by the lower apron 7 and in the feed guide placed over the feed belt to permit alinement of 60 the articles to be ironed with relation to the folding mechanism positioned at the opposite or discharge end of the machine. A machine of the type shown is particularly adapted for handling flat work, such as napkins, handkerchiefs, sheets, etc., and these articles are placed upon the feed belt, indicated at 9. This belt delivers each article to the rollers 3 and these in turn feed the articles across the upper ironing surface 2, 70 in this manner ironing one side. The articles, after passing over the upper ironing surface, are then received by the upper apron 5 and are next passed over the lower ironing surface 4 to smooth out or iron the 75 opposite side of the articles. The articles are finally passed between the upper and lower aprons and discharge over the roller, indicated at 8^a, where they are usually received by one or more operators who fold 80 and stack the articles in separate piles.

The present invention is provided for the purpose of automatically folding each article as it discharges over the roller 8^a, thus permitting the machine to operate with 85 greater speed and, furthermore, eliminating one or more of the operators which have previously been employed. The folding attachment consists of a plurality of individual, interspaced, parallelly disposed, endless 90 ropes, such as indicated at 11. These ropes pass over pulleys 12, journaled in the outer end of the folding frame generally indicated at C; then over a guide pulley 13 which directs the ropes back under the lower apron 95 7. The ropes then pass over idler pulleys, indicated at 14, and the upper roller 15 of the forward end of the lower apron. The several ropes are then passed over the forward roller 16 of the upper apron in a 100 position where they will lie between the upper and lower aprons, as indicated at 17. They then pass over the discharge roller 8^a and back to the rollers 12 in the forward frame shown, thus completing an endless 105 path of travel for purposes hereinafter to be described.

Extending crosswise of the frame B, forwardly and just above the feed belt 9, is a cross-bar 18, upon which is adjustably 110 mounted a plurality of guide fingers 19. These fingers are adjusted to assume posi-

tions approximately centrally of the inter-spaced ropes 11, and the articles, for instance napkins, to be ironed are placed upon the feed belt between said guide fingers. 5 This insures an alinement of the napkins, with relation to each individual rope 11, which is necessary as will later be seen. The napkins placed upon the feed belt between the guide fingers 19 are first delivered to the upper ironing surface 2, over which they are moved in the direction of arrow *a* by the action of the upper rollers 3. They are then received by the upper apron 5 and passed under the lower ironing surface 15 4 and are finally delivered to the rollers 15 and 16 where they are again returned in the direction of arrow *b* to the roller 8^a where they are carried off by each individual rope 11 and discharged by the folding mechanism, 20 as will be later described. Each napkin placed between the guide fingers 19, upon the feed belt 9, travels from this point in a straight line and, when delivered between the rollers 15 and 16, will be in perfect 25 alinement with one of the ropes 11. The pressure of the aprons causes the underlying rope to form a central crease in the napkin, which is completed by a flanged roller 30 positioned above the roller 8^a in alinement with each rope 11, there being one roller 30 for each rope. These flanged rollers, under which the ropes 11 pass carrying the napkins, as shown at 31, fold the napkin in a downward direction and further 35 increases the crease or fold which is partly formed by the pressure of the upper and lower aprons, thus completing the fold.

Each napkin will now travel from the 40 position indicated at 31 to the position indicated by dotted lines at 32, where they are removed by the operator and placed in separate piles. Each rope 11, traveling in the direction of arrow *c* across the frame 45 C toward the rollers 12, moves the napkins from the point 31 across the rollers 12 where they are received by a forwardly projecting arm or rod 33 placed in alinement with each roller and are here grasped and removed by 50 the operator.

From the foregoing description it will be seen that each napkin is ironed on both sides and folded centrally by the action of the ropes 11 and the rollers 30 and that it 55 is delivered to a point where it can be conveniently and quickly grasped and removed. If it is desired to again fold the napkin it can be accomplished either by the operator or any mechanism (not here shown); the object of the present invention being merely to 60 produce one central fold and to deliver the article at a point where it can be conveniently and quickly grasped by the operator. This permits the speed of the machine to be 65 considerably increased and the number of

operators previously employed may be reduced, as the operators are entirely relieved of making the first fold and the napkins are, furthermore, delivered to a point where they can be more easily removed.

By referring to Figs. 1 and 2, it will be seen that the frame C consists of two telescoping arms 34 and 35. The arm 34 supporting the rollers 12 may be extended or shortened to increase or decrease the tension of the co-operating rope and the telescopic mounting of the arm 35 permits the device as a whole to be raised or lowered, if it is desired to increase or decrease the number of ropes employed. For instance, 70 if handkerchiefs are being ironed, it is obvious that six or more of same may be placed upon the feed belt in alinement, thus requiring six rolls; while if large articles, such as towels or sheets are being ironed, it 75 is possible that only one or two rolls are employed. The adjustable mounting of the arms 34 and 35 is of considerable importance as it permits one or more of the ropes to be lowered and rendered inoperative. 80

The provision of the guide fingers 19 will probably now be appreciated. They are, practically speaking, necessary as it would otherwise be almost impossible to place the articles upon the feed belt in alinement 90 with the individual ropes. Any article not placed in alinement would, when discharged by the roller 8^a, overhang more or less on one side or the other of the rope, thus forming a fold out of alinement and causing 95 one side to overlap the other. The present feed guides have positively eliminated this and insure a uniform and perfect fold. 100

In the present illustration of the invention, the ropes 11 are shown as carried back under the lower apron, then over the roller 15 and finally forward between the upper and lower aprons and across the discharge roller 8^a to the roller 12. It is obvious, however, that the ropes might be 105 rearwardly of the discharging roller 8^a in a position where they would receive each article discharged, thus considerably shortening the length of the ropes and materially reducing the cost of the appliances of old. 110 The present arrangement is, however, preferable as it permits the formation of a preliminary crease before it is finally creased or folded by the flanged rollers 30. The flanged rollers 30 may in many instances be 115 entirely eliminated as the weight of the goods is, as a rule, sufficient to permit the ends to drop down and assume the position shown at 31. I therefore wish it understood that the rollers 30 may be eliminated, 120 if desired.

Secured to the adjustable arm 34 of the folding frame in any suitable manner is a spreading member, generally indicated at 40. The upper edge of this member is posi- 130

- tioned directly under the carrier or rope 11 and is constructed of a wire or thin sheet metal. The spreader is preferably V-shaped and is provided for the purpose of spreading 5 the lower ends of the napkin to prevent same from entering or catching in the pulley 12. There is one spreader for each carrier or rope 11 and the importance of same can readily be seen as they not only prevent 10 the ends of the napkins or other articles folded from getting caught or entering the pulley but also spread each article sufficiently to permit it to be delivered to the receiver 33.
- 15 The materials and finish of the several parts of the fold attachment, together with the feeding guides employed, may be such as the experience and judgment of the manufacturer may dictate.
- 20 I wish it understood that various changes in form, proportions and details of construction may be resorted to within the scope of the appended claims and that I do not wish to limit myself to the specific design and construction here shown.
- 25 Having thus described my invention, what I claim and desire to secure by Letters Patent is—
1. The combination with the discharge apron in an ironing machine, of a plurality of endless rope carriers traveling in alinement with and surrounding the discharge apron, and a folding member mounted in the path of travel of each carrier.
  - 30 2. The combination with the upper apron, the lower discharge apron and the feed belt in an ironing machine, of a plurality of feed guides mounted adjacent to the feed belt, and a folding mechanism mounted adjacent to the discharge end of the lower discharge apron.
  - 35 3. The combination with the upper apron, the lower discharge apron and the feed belt in an ironing machine, of a plurality of feed guides mounted adjacent to the feed belt, and a folding mechanism mounted adjacent to the discharge end of the lower discharge apron, said folding mechanism comprising a plurality of endless rope carriers mounted in alinement with the feed guides.
  - 40 4. The combination with the upper apron, the lower discharge apron and the feed belt in an ironing machine, of a plurality of feed guides mounted adjacent to the feed belt, a plurality of adjustable frames mounted adjacent to the discharge end of the lower discharge apron, and a plurality of rope carriers, one for each adjustable frame, passing between the upper and lower aprons and over guide pulleys in the adjustable frames.
  - 45 5. The combination with the upper apron, the lower discharge apron and the feed belt in an ironing machine, of a plurality of feed guides mounted adjacent to the feed belt, a plurality of adjustable frames mounted adjacent to the discharge end of the lower discharge apron, a plurality of rope carriers, one for each adjustable frame, passing between the upper and lower aprons and over guide pulleys in the adjustable frames, and a folding member mounted in the path of travel of each carrier.
  - 50 6. The combination with the upper apron, the lower discharge apron and the feed belt in an ironing machine, of a plurality of feed guides mounted adjacent to the feed belt, a plurality of adjustable frames mounted adjacent to the discharge end of the lower discharge apron, a plurality of rope carriers, one for each adjustable frame, passing between the upper and lower aprons and over guide pulleys in the adjustable frames, and a spreader positioned adjacent to the discharge end of the carrier.
  - 55 7. The combination with the upper apron, the lower discharge apron and the feed belt in an ironing machine, of a plurality of feed guides mounted adjacent to the feed belt, a plurality of adjustable frames mounted adjacent to the discharge end of the lower discharge apron, a plurality of rope carriers, one for each adjustable frame, passing between the upper and lower aprons and over guide pulleys in the adjustable frames, a folding member mounted in the path of travel of each carrier, and a spreader positioned adjacent to the discharge end of the carrier.
  - 60 8. The combination with the upper apron and the discharge apron on an ironing machine, of a plurality of endless rope carriers traveling in alinement with and between said aprons.
  - 65 9. The combination with the discharging apron in an ironing machine of an endless carrier traveling in alinement with the discharge apron, a frame, an upper and lower pulley journaled in said frame over which the endless carrier passes, and a rod secured to the frame in alinement with the upper pulley.
  - 70 10. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley, and a spreading plate mounted in the frame under the carrier in front of the pulley and rod and in alinement with the same.
  - 75 11. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 80 12. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 85 13. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 90 14. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 95 15. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 100 16. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 105 17. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 110 18. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 115 19. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 120 20. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 125 21. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.
  - 130 22. The combination with the discharging apron in an ironing machine of an endless carrier traveling in alinement with the discharge apron, a frame, an upper and lower pulley journaled in said frame over which the endless carrier passes, a rod secured to the frame in alinement with the upper pulley.

pulley, a spreading plate mounted in the frame under the carrier in front of the pulley and rod and in alinement with the same, and means for adjusting the position 5 of the lower pulley.

12. The combination with the discharging apron in an ironing machine of an endless carrier traveling in alinement with the discharge apron, a frame, an upper and lower 10 pulley journaled in said frame over which the endless carrier passes, a rod secured to the frame in alinement with the upper

pulley, a spreading plate mounted in the frame under the carrier in front of the pulley and rod and in alinement with the 15 same, and a flanged pulley mounted above the carrier ahead of the spreader.

In testimony whereof I have hereunto set my hand in the presence of two subscribing witnesses.

RICHARD LABORDA.
